AUTOMOTIVE VEHICLE HOOD ORNAMENT

Raoul J. Pepin, Ferndale, Mich., assignor to General Motors Corporation, Detroit, Mich., a corporation of Delaware

Application December 3, 1951, Serial No. 17,595

Term of patent 3½ years

(Cl. D14—18)

To all whom it may concern:

Be it known that I, Raoul J. Pepin, a citizen of the United States, being a resident of Ferndale, State of Michigan, have invented a new, original, and ornamental Design for an Automotive Vehicle Hood Ornament, of which the following is a specification, reference being made to the accompanying drawing forming a part thereof.

In the drawing:

Figure 1 is a top plan view of an automotive vehicle hood ornament, showing my new design.

Figure 2 is a side elevational view thereof.

Figure 3 is an end elevational view thereof looking from the left of Figure 2.

Figure 4 is a perspective view thereof.

I claim:

The ornamental design for an automotive vehicle hood ornament, substantially as shown.

RAOUL J. PEPIN.
